UNITED STATES PATENT OFFICE.

JOHN H. VIVIAN, OF CHICAGO, ILLINOIS.

DEVICE FOR PREVENTING OFFSETTING IN PRINTING-MACHINES.

SPECIFICATION forming part of Letters Patent No. 417,297, dated December 17, 1889.

Application filed June 24, 1889. Serial No. 315,391. (No model.)

To all whom it may concern:

Be it known that I, JOHN H. VIVIAN, a subject of the Queen of Great Britain, residing at Chicago, in the county of Cook and State 5 of Illinois, have invented certain new and useful Improvements in a Device for Preventing Offsetting on Printing-Machines, of which the following is a full and complete description.

10 I am aware that devices of various kinds have heretofore been employed for the purpose of preventing offsetting in the printing upon the reverse side of a sheet upon which there has already been printing recently done.

15 This invention may be placed upon a two or more cylinder web or hand-fed perfecting press or upon an ordinary two-revolution cylinder-press; and it consists, primarily, of a web spool or cylinder removably placed within 20 the impression-cylinder of the press and having thereon suitable webbing, (I prefer paraffined paper,) such webbing passing around the impression-cylinder of the press to and around a second and duplicate web 25 spool or cylinder, also removably placed within the impression-cylinder and interchangeable with the first-named removable spool, and means whereby the last-named web spool or cylinder is actuated either automatically 30 or at the will of the pressman operating the press. Where the device is placed upon a two-cylinder web-perfecting press, it is of course placed upon the second impression-cylinder of the press—that is to say, upon 35 the impression-cylinder by which the second side of the sheet is printed.

When my device is placed on an ordinary two-revolution cylinder-press, such press is designed to be used in conjunction with a 40 second press on which one side of the sheet is printed and from which the partially-printed sheet is transferred to the press on which my device is attached and the other side of the sheet printed while the first printed side 45 is yet damp and undried or unset, and it is for the purpose of permitting such immediate transfer to and printing on the second press that my device is applied to such second press.

50 I have illustrated my invention by the draw-

ings accompanying this specification and forming a part hereof, in which—

Figure 1 is an end elevation of an impression-cylinder of a printing-press with a portion of the end of the cylinder removed in 55 order to expose to view the herein-described device. Fig. 2 is a sectional view of the impression-cylinder on line 2 2 of Fig. 1, viewed in the direction of the arrows, an elevation of my device secured in such impression-cylinder, and a view of the respective connecting parts, whereby the device may be actuated. Fig. 3 is a sectional view of mechanism whereby one end of the web spools or cylinders may be secured in place in the impression-cylinder.

The manner in which the other end of the web-spools may be secured in position in the impression-cylinder is plainly shown at the extreme right of Fig. 2.

Like letters refer to like parts throughout the several views.

A is an impression-cylinder of the printing-press, A' the shaft or axle thereof, and A'' that portion of the frame of the press directly 75 in contact with and forming the support for the axle of the impression-cylinder.

B is a web-spool or web-cylinder, upon which the offsetting webbing is wound from web-spool B'.

B² is a revoluble shaft placed in the end of cylinder A, and when the web-spools B B', which are identical in construction, are placed in position in the impression-cylinder this shaft B² forms a continuation of the shaft 85 or axle of the web-spools and revolves therewith.

B³ is a spring pressing against web-spool B', with proper tension to prevent such spool from unwinding too freely. Upon each end 90 of the axle of the web-spools B B' there is formed the square hole b², into which (when the web-spools are in position in impression-cylinder A) the square end b' of pin b in shaft B² is pressed by spring b³. The other end of 95 the axles of the spools is held in recess a in the other end of the impression-cylinder A, as illustrated in Fig. 2. By withdrawing pin b from the hole b² in the axle of the web-spools B B' such spools may be taken from 100

the impression-cylinder and changed or replaced by others, which may be kept in stock with various widths of webbing wound thereon suitable to differing sizes of forms.

- 5 The web-spools B B' have at each end of the axles thereof the square hole b^2 , and may therefore be changed end for end at any time desired. I make use of this adaptability of changing the ends of the web-spool when inserting the same in the impression-cylinder in placing the web-spool B', from which the webbing is unwound, so that either side of such webbing will come in contact with the sheet upon which the form is being printed.
- 10 15 This enables me to use both sides of the paraffine-paper for preventing offsetting, and also by the hereinabove-described method to use paraffine-paper of substantially the width of the form in use upon the press.
- 20 25 30 C is the webbing of any suitable material; but, as hereinbefore stated, I prefer to use paraffined paper. This webbing C is wound on web-spool B from web-spool B' whenever it is necessary to change the part of the webbing which is around the impression-cylinder in order to prevent offsetting, and to thus wind the webbing upon the web-spool B, I place upon one of the shafts B^2 beveled friction-wheel D, and upon the axle of the impression-cylinder, not turning therewith but adapted to slide thereon, I place a second beveled friction-wheel D'. When the webbing is to be wound upon the web spool or cylinder B, the friction-wheel D' is slid into contact with spool friction-wheel D.

35 When my device is placed upon an ordinary two-revolution cylinder-press, I prefer to arrange the friction-wheel D' so that it may be slid by the pressman by handle d' into such contact with wheel D as in practice, owing to the variable kind of matter printed on such presses and the differing sizes of the forms, I deem it preferable to have the amount of webbing wound on web-spool B, and the time when it is so wound completely within the control of such pressman.

40 45 50 55 When the device is placed upon a two or more impression-cylinder web-perfected press, the movement of the friction-wheel D' may readily be made automatic, such automatic movement being secured by constructions adapted to actuate such friction-wheel D' in a manner to bring it into contact with the friction-wheel D. I have not illustrated such mechanisms, as they do not form a necessary part of my invention.

E are the common blanket-rods in the impression-cylinder, and F is the blanket secured to the rods E E.

60 65 The friction-wheels D D' may, it is evident, be omitted from the device, particularly when such device is placed upon a two-revolution cylinder-press, in which case in order to change the offset-webbing when necessary the press must be stopped in position, so that the web-spools, or one of them, may be turned by

the hands. While an operative device is thus secured without the use of the friction-wheels D D' and mechanism adapted to bring them in contact with each other I do not consider it advisable to so construct the device.

70 75 80 85 90 95 100 The manner in which this device operates is: After the press has been made ready to run with a suitable form thereon, web-spool B', having webbing C wound thereon, is placed within the impression-cylinder A, so that the webbing thereon may be unwound therefrom, thereby turning the web-spool B' to the right or to the left, as the one or the other side of the webbing is to come in contact with the sheets being printed on the press. The webbing C is then passed around the impression-cylinder A and secured to web-spool B, which is also placed in position empty in the impression-cylinder A, as hereinbefore described. The press is then run in the ordinary manner. If the movement of friction-wheel D' on shaft or axle A' be automatically regulated, and thereby brought into contact with the friction-wheel D, it is so arranged that such contact will occur when no type or other part of the form from which the impression is secured on the paper on impression-cylinder A is in contact therewith or with the webbing C. When the movement of the friction-wheel D' is controlled by the lever d' , such wheel is brought in contact with the wheel D whenever and so long as the pressman thinks necessary to bring into position on the impression-cylinder A so much of the webbing C as is required to prevent offsetting in the work being done.

105 Having thus described my invention and its method of operation, what I claim, and desire to secure by Letters Patent of the United States, is—
